UNITED STATES PATENT OFFICE.

CHARLES THERYC, OF MARSEILLES, FRANCE.

RAILWAY WITH SLIDING TRAINS.

No. 799,950.

Specification of Letters Patent.

Patented Sept. 19, 1905.

Application filed July 6, 1905. Serial No. 268,509.

To all whom it may concern:

Be it known that I, CHARLES THERYC, a citizen of the Republic of France, and a resident of Marseilles, France, have invented new and 5 useful Improvements in Railways with Sliding Trains, which improvements are fully set forth in the following specification.

At the Paris exhibition of 1889 a working model of a railway constructed by Messrs. 10 Girard and Barre, engineers, was exhibited. This model had vehicles moving on slippers raised by water-pressure and propelled hydraulically. The failure of that construction appears to have been due not only to the impractical method of propulsion, but also to 15 the excessive consumption of water by the slippers, which amounted to 3,600 liters per hour per ton of the train raised.

This invention has for its object to carry 20 out in a practical manner the sliding of a train drawn or propelled by electric or other locomotives, and, further, first, to reduce to a very small amount the supply and the loss of water due to sliding by means of a new form 25 of double slipper with balanced and compensated pressure; second, to insure in an absolute manner the stability of the vehicles by means of a guiding device with hydraulic sliding, whereby the previous dangers due to 30 high speed are avoided; third, to apply this process to existing railway-lines, so as to combine the sliding system with the existing method of traffic and to permit gradual transformation of the (rolling) stock and of the 35 system generally without interfering with the existing service.

Figure 1 is a cross-section through the vertical axis of a double slipper or slide according to this invention. Fig. 2 is a longitudinal 40 section through the vertical axis A B of the same double slipper. Fig. 3 shows the track or platform on which the vehicles and their guiding devices slide. Figs. 4 and 5 show the passages of the new track over existing 45 crossings. Fig. 6 shows the joints between each section of the platform. Figs. 7, 8, and 9 show diagrammatically modified constructions of the track or platform.

The main feature of this new construction 50 consists in a double slipper acting under balanced and compensated differential pressure, as shown in Figs. 1 and 2. It consists of an inner slipper *a* similar to that of Girard and Barre, with grooves *f* in its flanges *p*, which 55 are arranged like baffle-plates for the pur-

pose of slackening the speed of the discharge of the water. In the spherical surface *o* of the step-bearing *k* rests the rod *t*, which supports the vehicle. Over this inner slipper is arranged an outer slipper *b*, the shape of 60 which is the same as that of the first slipper. It is secured to a cylinder *b'*, which can slide with a certain amount of friction on the cylindrical portion *a'* of the inner slipper and is provided at *m* with a stuffing-box to prevent any leakage of water. In view of the 65 small relative movement of these two cylinders which need be produced and which is merely a fraction of a millimeter a rubber or similar ring ought to be sufficient as a 70 stuffing-box. Through the counter-slipper pass two water-inlet pipes *c*, passing through two cylinders *b''*, provided with stuffing-boxes *n*, the cylinders sliding with a certain amount 75 of friction on the pipes *c*. These pipes thus afford supplementary guiding for the purpose of maintaining for the two slippers the same axis during their divergent movement. Water is supplied under pressure to the interior of the slipper *a* through the tubes *c*, connected by 80 a hose-pipe to a collector which passes under all the vehicles and terminates at the engine, where a compressor forces the water under the slippers of all the vehicles. From each hose-pipe of the pipes *c* is branched off another 85 small hose-pipe, connected to a pipe *e* in such manner as to supply to the circular chamber *d* water under the same pressure as in the slipper *a*.

In order to show the advantages of the new 90 double slipper, the following explanations are necessary. Preliminary experiments, approximately confirmed by the working of the small sliding railway at the 1889 exhibition, have proved that the Girard-Barre slipper, 95 having an area of four hundred and forty by two hundred millimeters (nine hundred and sixty-eight square centimeters) and raising the weight of ten hundred and sixty kilograms, including the weight of the slipper, to the extent of 0.75 millimeters discharged or lost 100 0.963 liters of water per second. As the slipper worked under a constant pressure of 1.8 kilograms, it followed that the surface which acted in an effective manner was not nine 105 hundred and sixty-eight, but only five hundred and eighty-eight square centimeters, which corresponds to 1060: 1.8=588. This proved that the real perimeter of discharge was three hundred and seventy-eight by one 110

hundred and fifty-eight millimeters, which perimeter, multiplied by 0.75 millimeters of height and by 18.80 of the speed of flow under the pressure of 1.8 kilograms, ($\sqrt{g} \cdot 2 \cdot h$)

5 would give a flow of water equal to 15.117 liters through a free orifice. The grooves of the slipper, arranged in baffle-plate shape, broke the speed of flow and reduced the escape of water from the slipper to 9.693 liters, 10 thus giving a coefficient of contraction equal to 0.0637. It follows, therefore, from these experimental and practical data that the water acting under the slipper with a constant pressure of 1.8 kilograms escaped therefrom 15 with a pressure reduced to 1.8 by 0.0637—that is to say, to 0.115 kilograms—equivalent to a water-column of 1.15 meters.

In the improved construction the counter-slipper *b* being strongly applied against the 20 platform under a pressure of 1.8 kilograms exercised on the circular groove *d*, water could freely rise to the extent of 1.15 meters through the tube *h*, provided with a hose-pipe, into a tank, whence it would be withdrawn by the 25 compression-pump. The loss of water would thus be very small; but this method would have the great drawback of quickly wearing out the slipper-plates *s' s'*, of altering the platform, and of producing a perceptible resistance which 30 would have to be overcome. The working of the double slipper obviates these drawbacks. In fact, if by means of the sluice-valve *j* the cross-section of flow is throttled to a greater or lesser extent the pressure in the interval 35 or space *l* between the two slippers can be increased as desired. Under that resistance the slipper *a* will have the tendency to rise above its normal height of 0.75 millimeters until the counter-slipper *b* rises in its turn in order 40 to provide passage for a quantity of water which will be regulated at will to a layer or film just sufficient for doing away with the contact between the counter-slipper and the platform; but the loss of water, which would 45 be small even with a free discharge under a pressure lower than 1.8, will be reduced to a still more considerable extent by the contraction coefficient 0.0637 by arranging on the under side of the flange *p'* a network of grooves 50 *g* equal to or greater than the grooves *f* in the slipper *a*.

It will be seen that the differential pressures between the two slippers could be regulated in a moment in such a manner as to balance 55 and compensate them.

Sliding truck and hydraulic guiding.—The track is constituted by a platform 1, Fig. 3, forming a central plate 3, and two inclined slides 4, supported by one or more brackets 60 2, resting on the sleepers or on the brickwork to which the platform is bolted. Each vehicle slides on the platform 3 by means of wide double slippers 5. On the inclined sides 4 rest small slippers 6 of the same construction, arranged at the end of arms 8, connect-

ed to the framing of the vehicle. Between each small slipper and the arm is arranged a cylinder 7, in which moves a piston secured to the slipper, the said piston being compressed by a spring, so that the slipper can come into a lower position on the inclined side while remaining at right angles to it, the spring 9 being deflected. A rigid frame could, however, be used by transferring the springs supporting the vehicle above the frame. Such springs 75 could be helical or other springs and would be amply sufficient for the suppression of irregular movements. All deviation becomes absolutely impossible with this method of hydraulic guidance, the resistance of which and the expenditure of water by which are almost negligible.

The new track can pass over crossings 11, Fig. 4, in a very simple manner by means of drawbridges 13. In order to simplify the 85 drawing, a crossing at right angles has been shown; but it will be understood that the same arrangement applies to crossings at other angles. The plates 13, lowered by means of levers by the pointsman before the arrival of 90 the sliding train, are raised by him after its passage, so as to uncover the existing rails 11. The plates 13 could not be pivoted on hinges, as that would form a projection which must be avoided. Consequently these plates are 95 provided with a metal circle 14, forming a guide and leaving free an arc of three hundred degrees. When the plate is folded backward, the circle remains engaged to the extent of one hundred and twenty degrees with a 100 groove 15 of the same radius in the platform 3 and provided with rollers 16, which hold the circle in the position of rest and insure its moving without deviation during the rotation of the bridge 13. The two grooves 15 being 105 made near the angles of the platform 3 do not interfere in any way with the passage of the large slippers. The same arrangement is used for the small drawbridges or flaps for the inclined sides. In this way absolutely tight 110 joints are obtained by placing bands of rubber, leather, or even of wood or any other slightly elastic material on the inclined faces of the platform, which are to be provided with flaps, which bands deaden the shock when they 115 fold back.

It is also important to insure tight joints in the spaces provided between each section of platform for metallic expansion. To that end each section is provided at its two ends with 120 a groove 18, Fig. 6, into which are introduced with a certain amount of friction bars 17, having the shape of an inverted T and made of, say, resinous wood and of the size to suit the grooves. Two or three sets of these bars 125 with different thickness of web will have to be kept in stock, so as to change them according to the season. The line superintendent, by means of a plane secured to the end of a handle, would shave off from time to time the 130

asperities or roughness that would appear owing to the compression or crushing of the wood, due to the expansion of the metal. In this way a thoroughly tight joint would be 5 obtained.

The small guiding-slippers could be done away with by arranging the track with inclined or beveled sides and the supporting-slippers, as shown in diagrams in Figs. 7, 8, 10 9, for the purpose of effecting guidance only by means of the supporting-slippers. Fig. 7 shows a track identical with that already described, with a double supporting-slipper projecting over the beveled sides. Fig. 8 shows 15 a track with two inclined surfaces diverging from the center to the ends of the platform, on which slide two supporting-slippers of smaller width than the preceding one. Fig. 9 shows two inclined surfaces converging 20 downward from the ends to the center of the platform, on which slide slippers similar to the preceding ones, the even slippers sliding on one of the sides and the odd ones on the other. This construction would have the advantage 25 of enabling the taking of water to be effected quite naturally without stopping, in accordance with Ramsbottom's system used in England and in America. At the level portions of the track a canal or trough could be 30 arranged to which the water required both for the steam-locomotives and for the slippers could be supplied. Finally, for certain special lines—namely, for those intended for the movement of large weights—the number 35 of tracks and platforms could be multiplied and arranged in parallel.

For the sliding track a double-T girder of large size can be employed, the upper flange of which would be bent at the two ends so as 40 to form inclined sides arranged at a greater or lesser angle, or it could be constituted by means of two double-T girders of smaller dimensions, each double T having its outside flange bent down to form an inclined side 45 and the space between the two T-girders being filled with asphalt, cement, or any other suitable material flattened and exactly level with the height of the two T-irons.

Application to the existing rolling-stock.
50 *Period of transition.*—The sliding platform in the center of existing railway-lines could be arranged very quickly without interfering with the ordinary working and would be soon in the position to be used for very fast 55 trains with a new rolling-stock on sliding slippers; but during the transition period the old stock could be immediately utilized and arranged so as to take advantage of the many superior points of the sliding system. 60 While retaining the wheels of the existing vehicles double slippers would be arranged under their frame. On each supporting-rod *t* would be arranged a screw—or hydraulic—jack enabling the car to be raised and the 65 load carried by the axles and by the wheels

to be reduced to a minimum, so that the said wheels would retain just the necessary adhesion to the rails and their part would be reduced to that of supplementary guides. In this way the transition trains would be formed 70 before the present cars are gradually transformed by replacing their axles and wheels by slides. The transformation of the stock could thus be effected gradually and without discarding the existing stock. 75

Natural and emergency braking.—The sliding system constitutes in itself the simplest, the strongest, and the quickest method of braking that it is possible to imagine, this braking being done by closing the tap admitting water to all the slippers, and thus stopping hydraulic sliding and substituting for it a friction-grip between large surfaces. Wear will be very small, for during the working of the small railway in 1889 it was 85 proved that after about four thousand stoppages of that kind corresponding to twelve hundred kilometers traveled only a grinding action was noticed without any particular signs of wear. Besides, after a certain amount 90 of wear it will be simply sufficient to replace the plates *s* and *s'* of the slippers. This system of stopping and braking solves the problem of braking long trains, more particularly goods-trains, to solve which many unsuccessful attempts have been made. This is not the least advantage of the new practical sliding system according to this invention. 95

It will be seen from the above explanations that the advantages of the new system are as follows: An enormous reduction of the coefficient of resistance and of the expense in traction by the suppression of the important factor, "shocks and irregular movements," which is the cause of so many accidents and expense in the building and working of railways; great speed limited only by the power of the tractors and rendered safe by exceptional safety measures; absence of all shocks, vibration, noise, and smoke; application to 105 existing lines and stock, doubling or trebling 110 their efficiency as regards the carriage of useful weight; ideal and natural braking applicable to the longest trains. 115

I claim—

1. In a railway sliding system a sliding track in combination with double slippers on the vehicle with means for insuring differential balanced and compensated pressures substantially as set forth. 120

2. In a railway sliding system a sliding track double slippers on the vehicle in combination with lateral spring-controlled slippers, substantially as set forth.

3. In a railway sliding system a double slipper comprising an inner slipper with inward flanges an outer slipper with outward flanges and water-inlets to the interior of the inner slipper and the space between the two slippers substantially as set forth. 130

4. In a railway sliding system a double slipper comprising an inner slipper with inward flanges, an outer slipper with outward flanges, grooves g in the under sides of the flanges and 5 water-inlets to the interior of the inner slipper and the space between the two slippers substantially as set forth.

5. In a railway sliding system a double slipper comprising an inner slipper with inward flanges, an outer slipper with outward flanges, water-inlets to the interior of the inner slipper and the space between the two slippers, stuffing-boxes between the central projection of the inner slipper and between the inlet- 15 tubes thereof and the outer slipper, and a central chamber d in communication with the inlet-tube of the inner slipper substantially as set forth.

6. In a railway sliding system a double slipper comprising an inner slipper with inward flanges, an outer slipper with outward flanges, grooves g in the under sides of the flanges, water-inlets to the interior of the inner slipper and the space between the two slippers, 25 and a throttle-valve in the water-inlet to the outer slipper substantially as set forth.

7. In a railway sliding system a sliding double slipper with inclined outer edges in

combination with a correspondingly-formed platform-track substantially as set forth. 30

8. In a railway sliding system a platform-track with inclined slipper-surfaces meeting at the center in combination with correspondingly-inclined double slippers substantially as set forth. 35

9. In a railway sliding system a sliding double slipper with inclined outer edges in combination with a correspondingly-formed platform-track and folding crossing flaps 13, 14, 15, 16, substantially as set forth. 40

10. In a railway sliding system a double slipper comprising a slipper a , inwardly-extending grooved flanges s thereon, a central recess a' in said slipper, an outer slipper b , outwardly-extending grooved flanges p' there- 45 in and an annular chamber d in the outer slipper around the central recess of the inner slipper substantially as set forth.

In testimony whereof I have signed this specification in the presence of two subscr- 50
ing witnesses.
